Inventor.
Ernest Alschuler;
John M. Brumley
His Attorney.

UNITED STATES PATENT OFFICE..

ERNEST ALSCHULER, OF NEW YORK, N. Y.

ELECTRICAL CONNECTER.

Application filed February 10, 1923, Serial No. 618,424. Renewed December 27, 1926.

This invention relates to electrical connectors, such as may be used for connecting a plurality of circuits to one source of supply.

5 It is often desirable to connect a plurality of electric circuits to one source of supply and such supply being an ordinary house lighting circuit. A typical instance of such a case is that of Christmas tree lighting. In this class of lighting, the lamps are ordinarily connected in series in strings of eight, more or less. As this number of lamps is sometimes insufficient for larger sized trees, it is desirable to provide for connecting in two or more of such strings of lamps. This is often done by providing a connecting terminal located at a center of distribution and connecting the various circuits thereto by means of solder or screw 10 joints suitably insulated. This arrangement makes a more or less permanent connection and one that it is inconvenient to disconnect so that two, three or more strings of lamps are permanently connected together.

25 This invention has among its objects, therefore, to provide a connector which may be connected with the supply and which provides releasable connections in the form of plug sockets by means of which the various 30 circuits may be connected. This invention also provides a connector which may be connected to a given circuit intermediate its length without cutting the wires thereof.

Further objects will appear from the detail description taken in connection with the accompanying drawing, in which:

Figure 1 represents a connector embodying this invention; and

Figure 2 is a view of the connector of Figure 1 with one of the halves removed so as to disclose the interior connections.

Referring to the accompanying drawing, the connector comprises an insulating body made in two connectible half parts 1 which 45 may be practically duplicates of each other and arranged to fit together face to face. Each of these parts is provided with recesses 2 longitudinally thereof and end flanges 3 adapted to provide abutments for the plugs. 50 Arranged transversely of the recesses 2 is a pair of openings 4, each provided with a surrounding boss 5. These openings provide an inlet for the supply circuit and a channel connecting the same with an outlet 55 for an extension thereof. The connection

may thus be attached at any intermediate portion of a flexible cord.

Arranged within the recesses 2 is a pair of metallic contacts 6, each provided with an end portion 7 bent back upon the connector so as to provide a spring clip located just within the end opening of the recess 2. Each connector 6 is provided near the middle thereof with a lip 8 provided with a socket for a clamping screw 9, by means of which the wires 10 of the supply circuit may be connected to the contacts 6 as illustrated in Figure 2. It will be noted that such connection may be made at any point in the length of the wire by simply stripping appropriate portions of the two wires and making connections by means of the screws 9 as illustrated. The screws 9 being displaced relatively provides that the stripped portions of the wires 10 do not come opposite each other but each stripped portion lies opposite an insulated portion of the adjacent wire. This insures adequate insulation between the wires at all points. After connecting the wires, the two half portions may be placed one upon the other so as to cover the connections and the contacts 6 and may then be secured in assembled relation by means of screws 11 or other suitable fasteners.

80 The branch circuits 13 which are to be connected to the supply circuit may each be provided with a plug 12 provided with a pair of blades 14 adapted to enter the recesses 2 and contact with the clips 7. The 85 clips 7 by their spring action hold the plugs in place in the socket.

It will be noted that this invention provides convenient and durable means for connecting a series of circuits to a single supply. 90 With such a connector in use, each of the separate branch circuits may be handled individually in arranging the same as in the case of the Christmas tree lights above mentioned, so as to avoid entangling the various 95 circuits with each other and other awkwardness in handling the same. Each circuit may be arranged individually and thereafter attached by means of its plugs. Similarly in dismounting the lamps the plug may first be 100 removed and then the lamps disengaged.

105 It is obvious that various changes may be made in details of construction without departing from the spirit of this invention; it is, therefore, to be understood that this 110

invention is not to be limited to the specific details shown and described.

Having thus described the invention, what is claimed is:

- 5 1. A plural socket connector for attachment to the wires of a continuous flexible cord, comprising, a body having a socket at each end thereof and having a channel extending therethrough transversely of said 40
10 sockets adapted to receive the traversing wires, and terminal connections within said body and adapted for attachment to the wires and provided with contacts adapted for engagement by plugs inserted in said 15 sockets.
2. A plural socket connector for attachment to the wires of a continuous flexible cord, comprising, a body having a socket at each end thereof and having a channel ex- 50
20 tending therethrough transversely of said sockets, said body being adapted for placement over an intermediate portion of the cord with the wires thereof within and traversing said channel, and terminal connec- 55
25 tions within said body and adapted for attachment to the wires and provided with contacts adapted for engagement by plugs inserted in said sockets.
3. A plural socket connector for attach- 60
30 ment to the wires of a continuous flexible cord, comprising, a body composed of two connectible halves adapted to be placed over an intermediate part of the cord, said body having a socket at each end thereof and hav- 65
